J. W. SCHADE

SAFETY DEVICE FOR MACHINES

Filed Dec. 28, 1921

Fig. 1

Patented Feb. 24, 1925.

UNITED STATES PATENT OFFICE.

JAMES W. SCHADE, OF AKRON, OHIO, ASSIGNOR TO THE B. F. GOODRICH COMPANY, OF NEW YORK, N. Y., A CORPORATION OF NEW YORK.

SAFETY DEVICE FOR MACHINES.

Application filed December 28, 1921. Serial No. 525,344.

To all whom it may concern:

Be it known that I, JAMES W. SCHADE, a citizen of the United States, residing at Akron, in the county of Summit and State 5 of Ohio, have invented a certain new and useful Safety Device for Machines, of which the following is a specification.

This invention relates to safety devices for machines and is particularly applicable 10 to beam presses of the type commonly used for die-stamping sheet material such as sheet-metal, leather or rubberized fabric.

My object is to provide an improved safety device adapted to insure that the operator 15 will not be injured by operating the machine while either of his hands remains therein, and I attain this object by providing a latching mechanism requiring the use of both hands of the operator outside of the 20 machine to release the actuating mechanism.

Of the accompanying drawings, Fig. 1 is 25 a front elevation of a beam press embodying a preferred form of my invention, with the work and a cutting die therein.

Fig. 2 is a detached rear elevation, with parts broken away, of a part of my device.

Fig. 3 is a section on line 3—3 of Fig. 2.

Referring to the drawings, 10 represents generally a beam press comprising an adjustable lower platen 11, a die block 11^a 30 justable on thereon, adjusting screws 12, 12 for raising and lowering said platen, a cross-beam or moving upper platen 13 secured upon vertically slidable bars 14, 14, and a cam-shaft 15 for actuating said upper platen 35 through eccentric cams (not shown) secured to said shaft just inside the end standards 16, 16, said cams coacting with pitmans (not shown) hinged to the lower ends of the bars 14, the construction and operation of such 40 parts being well known in the art. 16^a is a cutting die and 16^b is the work in place.

The cam shaft 15 is provided with a male cone clutch member 17 secured thereon and 45 coacting with a shiftable, constantly driven, belt pulley 18 constituting a female cone-clutch member, for turning the cam-shaft 15 to operate the press at the will of the operator. 19 is a shipper lever fulcrumed at 50 20 on a bracket 21 extending from the frame of the press, for engaging and disengaging the clutch, said lever being actuated by a push rod 22 hinged to its upper end and connected through a pair of bell crank levers 55 55, 23, pivoted on the frame of the machine,

and treadle rods 24, 24, with a treadle 25, the latter being secured at the rear of the machine to a rock-shaft 26 and connected to the frame of the press by springs 27, 27 tending to hold said treadle in its upper 60 position, with the clutch disengaged. 28 is a brake-drum secured to the cam-shaft 15 and coacting with a brake shoe 29 pivoted on a bracket 30 extending from the frame and adapted to be raised against the brake-drum by an arm 31 secured to the rock shaft 26.

Upon the frame of the press, a plate 32 is secured by means of screw bolts 33, 33, and 70 slidably mounted in guide brackets 34, 34 on the rear face of this plate is a vertical bar 35 formed with latch-recesses 36, 36, said bar being connected with the treadle 25 by an adjustable link 37.

Pivoted on the rear face of the plate 32, 75 at 38, 39 respectively, are two latch members 40, 41 having the form of bell crank levers, their upwardly extending arms being provided respectively with latch-pawls 42, 43, adapted to enter the latch recesses 36 80 under the action of tension springs 44, 45 connecting the horizontal arms of the respective bell crank levers with the plate 32. Said arms are slotted respectively to receive vertically swinging pins 46, 47 extending 85 through slots 48, 49 in the plate 32, from mountings presently to be described, said pins being adapted to swing the bell-crank levers to engage and disengage the latch-pawls 42, 43 with respect to the bar 35, 90 this structure being adapted normally to latch the bar 35 in an elevated position and thus prevent the depression of the treadle 25 and consequent closing of the press.

Secured to the front face of the plate 32 95 by screw bolts 50, 50, and extending forward through the frame of the press, are brackets, one of which is shown at 51, Fig. 3, formed with notches 52, 52 at their outer ends, to seat a pair of horizontal pipes 53, 54, and 100 interfitting with plates 55, one of which is shown in Fig. 3, through which plates the pipes extend, said plates 55 being drawn toward the brackets 51 by screw bolts 56, 56 (Fig. 2) extending through the plate 32, 105 to hold the pipes 53, 54 securely in position in the notches 52 of said brackets.

Extending through the pipes 53, 54 and 110 rotatably mounted in end caps 57, 57 secured to said pipes are rock-shafts 59, 60,

from which extend the pins 46, 47 for turning the latch members 40, 41, said pins extending through vertical slots (54^a, Fig. 3) in the pipes 53, 54 and through the slots 5 48, 49 in the plate 32, to the forked ends of said latch members.

For turning the rock-shaft 59, 60 I provide on each a plurality of short, spaced-apart hand levers 61, 61, 62, 62, the intermediate ones of which extend through vertical slots 63, 64, in the pipes 53, 54.

In the operation of the press, one each of the two sets of hand levers 61, 62, are raised, turning both rock-shafts 59, 60, 15 swinging the pins 47, 46 downward, and thereby turning the latch members 41, 40 on their pivots to release the vertical bar 35, which, through the link 37, normally prevents the depression of the treadle. The 20 latter is then depressed by the operator's foot, releasing the brake-shoe 29 from the brake-drum 28, and, through the treadle rods 24, bell-crank levers 23, push rod 22 and shipper lever 19 shifting the revolving 25 belt pulley 18 into engagement with the cone-clutch member 17 rotating the cam-shaft 15 and thereby actuating the press. As the platen 13 rises, the operator removes his foot from the treadle, which is then raised 30 by the springs 27, applying the brake 28, 29, and raising the bar 35, which latter is again latched in its upper position by the latch members 40, 41, by reason of the springs 44, 45 and the weight of the hand levers 61, 62 turning said latch members and 35 the rock-shafts 59, 60 into latching position.

I prefer to have the latch recesses 36 in the bar 35 of substantial length, as here shown, in order that sufficient time will be 40 given for said parts to be returned to latching position, thus assuring that the recesses will not be jumped by the pawls 42, 43, it being essential only that their upper ends in moving downward shall engage the pawls 45 and be stopped thereby before the clutch is thrown in, except when the hand levers 61, 62 are held in releasing position.

To release the bar 35 and permit the press to be closed, both of the rock-shafts 50 59, 60 must be turned by hand, and the hand levers on the two are so positioned that the operator is required to use both hands to do this. It is thus assured that the press will not be closed with either of 55 his hands between the platens. The several hand levers are so disposed along the rock

shafts, however, that as the operator changes his position along the front of the press, he always has a lever of each set within his reach.

The device is of simple construction and is easily detachable. It may be modified without departing from the scope of my invention, and I do not wholly limit my claims to the specific construction here shown.

I claim:

1. In apparatus of the character described, the combination of a power applying member, a pair of latch members adapted independently of each other to hold said power applying member out of operative position, rock shafts arranged lengthwise of one side of the apparatus and adapted respectively to retract said latch members, and a plurality of hand-levers on each of said rock shafts, said hand levers being so positioned that the operator, standing at different positions lengthwise of said rock shafts can reach a hand lever on each rock-shaft with his two hands at the same time, but cannot do so with one hand.

2. In a safety device for a power-driven machine, a pair of substantially parallel rock shafts both adapted to be turned for the starting of the machine, and a plurality of spaced-apart handles projecting laterally from each of said rock-shafts, the handles on one shaft alternating with those on the other shaft to form successive pairs of handles longitudinally spaced apart, the successive pairs of handles being close enough together to be grasped at the same time by the respective hands of an operator but not close enough to be so grasped by one hand.

3. In a safety device for a power-driven machine, the combination of power-starting means, and two series of spaced-apart control members disposed along one side of the machine, a member of each of said series being required to be at the same time engaged by the operator for actuating said power-starting means, and said members being so positioned that the operator, at all stations along the series, can at the same time engage a member of each series with his respective hands but cannot do so with one hand.

In witness whereof I have hereunto set my hand this 23 day of December, 1921.

JAMES W. SCHADE.
